W. E. KIDNEY

POWER DRIVEN GRINDER

Filed Feb. 10, 1923

UNITED STATES PATENT OFFICE.

WILLIS E. KIDNEY, OF CLEVELAND, OHIO, ASSIGNOR TO THE CLEVELAND ELECTRIC
MACHINE & MFG. CO., OF CLEVELAND, OHIO, A CORPORATION OF OHIO.

POWER-DRIVEN GRINDER.

Application filed February 10, 1923. Serial No. 618,266.

To all whom it may concern:

Be it known that I, WILLIS E. KIDNEY, a citizen of the United States, residing at Cleveland, in the county of Cuyahoga and State of Ohio, have invented a certain new and useful Improvement in Power-Driven Grinders, of which the following is a full, clear, and exact description.

The present invention relates to power driven grinders of the screw type such as used for grinding meat. In the operation of grinders in the type referred to there is a very heavy back-thrust upon the drive shaft due to the back pressure of the material against the screw, which in machines as heretofore constructed has caused considerable trouble, in that the bearings wear rapidly causing the drive shaft to wobble, creating a condition in which there is an undue amount of friction in the bearings and an imperfect engagement of the driving gears. Furthermore, in machines as heretofore constructed, a large part of the wear has been upon parts of the drive-shaft itself with the result that the life of the drive shaft has been comparatively short, requiring frequent replacement.

It is the object of the present invention to provide means for taking up the back thrust on the drive shaft without subjecting any part of the drive shaft to excessive wear.

A further object is to provide thrust bearings which may be readily removed and replaced without disconnecting the drive shaft and driving gears.

A further object is to so mount the drive shaft that wobbling is prevented even though the thrust bearings become worn.

Other objects will be apparent from the following description and accompanying drawings.

The following description and accompanying drawings set forth in detail certain means embodying the invention, the disclosed means, however, constituting but one of the various mechanical forms in which the principle of the invention may be employed.

Reference should be had to the accompanying drawings forming a part of this specification, in which Fig. 1 is a side elevation of the machine, a portion of the stand being broken away to show the thrust bearing; Fig. 2 is a horizontal section through

the supporting stand and gear housing showing the mounting of the drive shaft. 55

Referring to the accompanying drawings, the supporting stand 1 is usually in the form of a hollow casting having a flat top 2 upon which is secured the motor 3 for driving the grinder. The supporting stand 1 has at the front end thereof a widened and upwardly extending portion 4 adapted to form part of the housing for the gearing which transmits movement from the motor shaft to the 60 grinder drive shaft. 65

The grinder casing 5 has a forwardly extending portion adapted to enclose the grinder screw and a portion 6 at its rear end adapted to fit upon the housing portion 4 of the stand and completing the gear 70 housing. The housing portion 6 of the grinder casing is detachably secured to the housing portion 4 of the stand so that access may be had to the gearing when the grinder casing is disconnected from the supporting stand. The grinder casing 5 has a head portion 7 at its forward end in which the perforated disc through which the material is forced may be secured and a hopper portion 8 into which the material to be 75 ground is placed.

Within the forwardly extending portion of the casing 5 there is rotatably mounted a screw 9 which has a squared shaft portion at its rear end adapted to fit in a square socket at the end of the driving shaft. The drive shaft 11 is journalled within the upper part of the supporting stand 1, extends through the stand from front to rear in axial alignment with the grinder screw 9, and has an enlarged front end portion 12 provided with a square socket to receive the squared end 10 of the screw shaft. The enlarged end portion 12 of the drive shaft is journalled in a bearing boss 13 at the rear end of the 85 grinder casing 5, and is provided with a flange 14 at its rear end engageable with the boss 13 to limit the forward movement 90 of the drive shaft. 95

Splined upon the drive shaft 11 is a gear wheel 15 which has an integral rearwardly extending sleeve 16 journalled in the front wall of the supporting stand 1. The gear 15 is within the gear housing formed between the adjoining ends of the supporting stand and grinder casing and is driven from 100 105

the shaft 17 of the motor by means of a gear 18 on the motor shaft 17 which meshes with a gear 19 on a countershaft 20, which has fixed thereto a small gear 21 meshing with 5 the gear 15 on the drive shaft.

The rear wall of the supporting stand 1 is formed to provide an open ended bearing boss 22 through which the rear end of the driving shaft 11 extends. The driving shaft 10 11 has a reduced rear end portion 23 forming at the inner end thereof a thrust shoulder 24 through which the thrust of the shaft is transmitted to the thrust bearings. The thrust bearings for the drive shaft 11 fit 15 within the boss 22 in the rear wall of the supporting stand and consist of a front washer 25 fitting over the reduced end portion 23 of the shaft and engaging the thrust shoulder 24, and rear washer 26 also fitting within 20 the boss 22 and over the reduced end of the shaft 23 and balls 27 interposed between the washers 25 and 26.

The thrust bearing is secured in place within the boss 22 and against the thrust shoulder 24 of the shaft by means of a detachable cap 28 which has an inner portion fitting within the boss 22, flanges overlying the outer end of the boss and bolted thereto, and a rearwardly extending bearing portion 29 within which the end of the reduced portion 23 of the shaft 11 is journaled.

In the operation of the machine the back thrust of the screw is transmitted through 35 the shaft 11 to the washer 25 of the thrust bearing. By reason of this arrangement the entire thrust of the shaft is taken by a single bearing at its rear end. Wear upon the thrust bearing will merely result in a slight 40 rearward movement of the drive shaft which will be permitted by the bearings at the front and rear ends of the shaft. In view of the fact that the drive shaft is journaled in bearings at its front and rear end 45 which receive none of the rearward thrust of the shaft and in which the shaft may have a limited sliding movement, wear upon the thrust bearing will not cause wobbling of the drive shaft. If the thrust bearing 50 becomes worn, it can be readily removed and replaced by removing the cap 28.

Having described my invention, I claim:

1. A power driven grinder, comprising a supporting stand, a motor carried by said stand, a grinder casing detachably secured to the front end of said stand, a screw in said casing, a drive shaft for said screw extending through the supporting stand and

journaled therein, said shaft being directly connected to said screw, said drive shaft having a reduced rear end portion providing a thrust shoulder, and said supporting stand having a bearing receiving recess at its rear end, gearing connecting said motor and shaft, and a removable thrust bearing upon the reduced rear end of said shaft and fitting within the recess at the rear end of the stand.

2. A power driven grinder, comprising a supporting stand, a motor carried by said stand, a horizontally disposed grinder casing detachably secured to the front end of the stand, a screw in said casing, a horizontal drive shaft aligned with the axis of said screw and having a detachable driving connection at its front end to said screw, said drive shaft extending through the supporting stand and journaled therein, said drive shaft having a reduced rear end portion providing a thrust shoulder, and said supporting stand having a bearing receiving portion at its rear end, a thrust bearing on said reduced end portion of the shaft engaging said thrust shoulder and fitting within said bearing receiving portion of the supporting stand, a cap detachably secured to said stand for securing said thrust bearing in place, and gearing connecting said motor and stand.

3. A power driven grinder comprising a supporting stand, a grinder casing having a forwardly extending screw receiving portion adapted to be detachably secured to the stand, a screw in the grinder casing, a drive shaft extending through the stand and journaled therein, said drive shaft being axially aligned with said screw and having a driving connection therewith through which it is adapted to receive the back thrust of the screw, said shaft having a reduced rear end forming a thrust shoulder, an open ended cylindrical bearing boss in the rear wall of the supporting stand, a thrust bearing on the reduced rear end of the shaft engaging the thrust shoulder thereon and fitting within said open boss, a cap detachably secured to the stand over the outer end of said open boss for securing said thrust bearing in place, said cap having a bearing portion to receive the end of the shaft and gearing within the gear housing connecting said motor and shaft.

In testimony whereof, I hereunto affix my signature.

WILLIS E. KIDNEY.
